UNITED STATES PATENT OFFICE.

ALBERT LEGGEMANN, OF BRUNSWICK, GERMANY.

DISINTEGRATING MILL.

Application filed February 26, 1927, Serial No. 171,312, and in Germany January 31, 1927.

My invention relates to improvements in disintegrating mills, and more particularly in mills of the type in which one or more rotary beaters cooperate with a grate in the form of a funnel, the said beaters passing between the grate bars and acting on the material placed thereon by impact. The object of the improvements is to provide a mill of this class which has a high efficiency and in which obstruction of the bottom part by the material being disintegrated is avoided. With this object in view my invention consists in providing an abutment at the bottom part of the funnel provided by the grate on which the material being disintegrated is supported, so that the beaters have a full action thereon.

For the purpose of explaining the invention an embodiment of the same has been shown in the accompanying drawing in which the same reference characters have been used in all the views to indicate corresponding parts. In said drawing,

Fig. 1, is a vertical section of the mill, Fig. 2, a top plan view thereof with parts broken away for clearer disclosure, and Fig. 3 is a side view of the abutment at the bottom part of the funnel.

In the example shown in the figures my improved mill consists of two parallel sections each comprising a rotary shaft h having beaters q, s mounted thereon, the said sections having a chute b disposed between the same. The side walls of the chute are formed of grate bars a , and the hammers or beaters being rotated pass between the said grate bars and into the hopper provided thereby so as to act on the material to be disintegrated.

Referring now more particularly to the drawing, the mill comprises a frame g provided with a transverse tapering member t and cross-bars v . On the said tapering member an elongated head u of tempered steel is supported, and on the cross-bars v and the said tapering member segmental bars f are supported, which are connected by grate bars f^1 and cross bars f^2 . Above each of the grates f, f^1 a shaft h is rotatably mounted in bearings i secured to the frame g , and the said shafts are adapted to be rotated by suitable means such as belt gearings j . At their adjacent top ends the segmental bars f are supplemented by segmental grates a , the distance of which from the axes of the respective shafts h is less

than the distance between such axes and the coacting grates f , and which are disposed so as to provide a hopper b adapted to have the material to be disintegrated delivered into the same. Further, each mill is covered by a segmental wall n having openings o normally closed by lids p . To each of the rotary shafts h a plurality of arms q are fixed, the length of which is less than the distance of the segmental grates a from the respective shafts h . On pivot bolts r fixed to the outer ends of the said arms beaters or hammers s are rockingly mounted, which hammers are adapted to pass between the bars of the grates a . Thus, upon rotation of the shafts h the hammers or beaters pass into the hopper b where they act on the material to be disintegrated. The disintegrated material falls through the grates a and on the grates f, f^1 where it is further reduced by the hammers moving across the said grates. So far the disintegrating mill is known in the art.

In the operation of the mill the material fed into the funnel b tends to obstruct the bottom part of the grates a , so that the action of the hammers or beaters s on the material is interfered with. Therefore I provide an elongated anvil c at the bottom part of the hopper b , which anvil is supported by arms d on the grate bars a . The portions e of the said anvil located between the arms d have a substantially triangular or wedge-shaped cross-section, and they have a rounded top part, suitable means being provided for fixing the said anvil to the grates a . Further, the portions e are supported on the elongated head u . Thus the anvil can be readily removed in case of wear and replaced with a new one. The triangular part of the anvil is spaced from the bottom part of the grates a , and in the operation of the mill it provides a rigid support for the parts of the material falling to the bottom part of the hopper, so that the beaters or hammers s have a strong disintegrating action.

While in describing the invention reference has been made to a particular embodiment of the same I wish it to be understood that my invention is not limited to the construction shown in the drawing, and that various changes may be made in the general arrangement of the apparatus and the construction of its parts without departing from the invention, the true scope of which is indicated in the appended claims.

I claim:

1. A disintegrating mill, comprising a hopper for the material to be disintegrated having its bottom in the form of a grate, rotary beaters adapted to pass between the bars of the grate into said hopper, and a rigid abutment located above the bottom part of said hopper and spaced from the bottom part of said grate.
- 10 2. A disintegrating mill, comprising a pair of segmental compartments, parallel shafts rotatably mounted one in each of said compartments, beaters mounted on said shafts, a hopper above said compartments and common to both compartments, the side walls of said hopper consisting of segmental grates formed with slots located concentrically of said shafts and having a distance from said shafts such that the outer ends of 15 said beaters are adapted when being rotated to pass between the same and into said hopper, and an elongated anvil above the bottom part of said hopper and having its side walls spaced from the bottom parts of the 20 side walls of said hopper.
- 25 3. A disintegrating mill, comprising a pair of segmental compartments, parallel shafts rotatably mounted one in each of said compartments, beaters mounted on said shafts, a hopper above said compartments and common to both compartments, the side 30 walls of said hopper consisting of segmental grates formed with slots located concentrically of said shafts and having a distance from said shafts such that the outer ends of said beaters are adapted when being rotated to pass between the same and into said hopper, and an elongated anvil above the bottom 35 part of said hopper and having its side walls spaced from the bottom parts of the side walls of said hopper, said anvil being removably fixed to the side walls of said hopper.

walls of said hopper consisting of segmental grates formed with slots located concentrically of said shafts and having a distance from said shafts such that the outer ends of 35 said beaters are adapted when being rotated to pass between the same and into said hopper, and an elongated wedge-shaped anvil disposed at the bottom part of said hopper and spaced from the bottom parts of the side 40 walls thereof and formed with laterally projecting arms bearing on said side walls.

4. A disintegrating mill, comprising a pair of segmental compartments, parallel shafts rotatably mounted one in each of said compartments, beaters mounted on said shafts, a hopper above said compartments and common to both compartments, the side walls of said hopper consisting of segmental grates formed with slots located concentrically of said shafts and having a distance from said shafts such that the outer ends of 45 said beaters are adapted when being rotated to pass between the same and into said hopper, and an elongated anvil at the bottom 50 part of said hopper and spaced with its side walls from the bottom parts of the side walls of said hopper, said anvil being removably fixed to the side walls of said hopper.

In testimony whereof I have hereunto set 55 my hand.

ALBERT LEGGEMANN.
